DIRECTIONAL AERIAL

Walter van B. Roberts, Princeton, N. J., assignor
to Radio Corporation of America, a corporation
of Delaware

Application March 1, 1929. Serial No. 343,710

2 Claims. (Cl. 250—33)

In radio direction finders known heretofore of the type which use a rotatable loop aerial much difficulty has been encountered in obtaining a system in which at zero response in the receiver 5 energized thereby, the loop aerial will be pointing directly toward the source of energy.

This inaccuracy in true pointing position is due in part to distorted wave front and in part to characteristics inherent in the apparatus used 10 such as, for instance, 1—out of phase currents caused by the vertical aerial or electrostatic effect of the signal voltage on the tuned loop when the loop is unsymmetrical with respect to ground. This effect is present whether the wave front is 15 distorted or not; 2—currents due to signal voltage across a loop of some axial length caused by a distorted wave front having horizontal component of the electric field. This voltage is in phase with the electrical field and the amount 20 thereof changes as the loop is rotated, and the current set up thereby is either in phase or 180° out of phase with respect to the normal loop effect thereby distorting the normal loop characteristic curve. This effect is present whether the loop is 25 symmetrical or not, and results in shifting the point of zero response so that the loop does not point directly toward the source of energy when signal response is minimum. Aerial systems 30 of the above type are subject to various other inherent defects caused either by unsymmetrical apparatus, or thereby when effected by unsymmetrical signal waves, however, those pointed out above will serve for purposes of illustration.

Heretofore various means have been provided 35 to compensate the various errors above referred to by adding current in the proper phase to more or less compensate the error causing currents introduced in each of the above mentioned ways. Such means known heretofore has necessitated 40 the use of considerable additional apparatus.

The primary object of this invention is to provide a new and simple method of correcting the null points of a loop shifted from true pointing 45 position by the effect of a component of the electric field along the axial length of the loop.

Another object of this invention is to provide a loop in combination with simple means for compensating the error therein which once adjusted will remain permanently adjusted for all 50 wave lengths received on the loop.

A better understanding of the invention and the operation thereof will be had from the following detailed description of the invention and 55 therefrom when read in connection with the annexed drawing throughout which like references indicate like parts and in which

Figure 1 illustrates how the horizontal component of the electric field acts on a tuned coil having appreciable length;

Figure 2 shows a method of winding an inductance coil to overcome the difficulties encountered with apparatus as illustrated in Figure 1;

Figure 3 shows novel correcting apparatus arranged to correct the error in the coil of Figure 65 1 in accordance with the present invention; while

Figure 4 shows a receiving circuit connected with an aerial system which includes my novel method of reducing error applied to a balanced frame aerial and a vertical aerial coupled to said 70 frame aerial to obtain in the receiver a cardioid characteristic curve.

Referring to the drawing and in particular to Figure 1 which shows a solenoidal coil or loop 1 tuned by means of a variable capacity 2. When 75 the axis X of the coil coincides with the direction of propagation of the signals we would normally have no current produced in the coil. But, if the wave front is distorted as indicated by the heavy line W F of Figure 1 in addition to the 80 expected vertical electric field which is perpendicular to the axis of the coil there would exist an electric component along the direction of signal propagation, and then when the axis of the coil coincides with the direction of signals a considerable current will be produced by this horizontal electric component. This is, of course, 85 due to the fact that the incoming wave which tends to vary the potential of all objects it meets, hits one end of the coil first and thus causes a 90 difference of potential between the ends of the coil. This difference in potential in turn sets up currents. As a result such a coil generally does 95 not give a true indication of direction at its position of minimum signal response. The object of the present invention is to provide a simple means for compensating and eliminating the error introduced in the above manner.

The difficulty may be obviated by using two 100 coils wound in opposite directions with their axis parallel as shown in Figure 2. The above mentioned trouble does not exist in this case because when an incoming electric field is in the direction of the axis of the coil itself it strikes both ends of the tuned circuit at the same instant, thus 105 maintaining the potentials at the two ends equal and hence producing no current even though the field of the approaching wave is distorted. Figure 2 is only one of a number of symmetrical arrangements which may be used to avoid the 110 trouble.

It is possible however, to cure the trouble without going to the extra complication of making the structure symmetrical. A modification showing an arrangement for eliminating such errors in accordance with the present invention is illustrated in Figure 3. In this modification two conductors 3 and 4 from the right and left sides respectively of coil 1 are run out to receive com- 115 120

pensating differences of potential. The length of the conductors are determined by trial and error and once determined for a certain coil need not be again altered. It will be seen that the 5 incoming wave strikes the conductor 4 extending from the left end of the coil to the right first and thus offsets the fact that the wave strikes the right hand end of the coil first. Likewise a wave approaching from the left of Figure 3 will strike 10 the conductor 3 first and thereby compensate the effect which would otherwise be present in the coil due to the fact that the wave strikes the left hand end thereof first.

My invention is preferably used in connection 15 with other means known in the art for convenient operation of direction finders including auxiliary means for determining the sense as well as direction of the source of radiant energy.

In Figure 4 which shows the at present preferred embodiment of my invention the loop antenna 1 is provided with crossed electric pickup conductors 3 and 4 provided for the purpose of eliminating error normally caused by the current due to horizontal components of an electric field. 25 The length of these pickup conductors is ascertained by trial and error for a particular loop and operate in the same manner in which the conductors 3 and 4 of Figure 3 operate. Sense of direction is obtained by means of a vertical aerial 30 5 tuned by a variable capacity 6, coupled through a series inductance 7 to an inductance 8 in series with the loop circuit 1, 2. By tuning the aerial 5 and adjusting the coupling between coils 7 and 8 current due to the vertical aerial effect in 1 35 can be introduced in the loop circuit in proper phase and amplitude to combine with the current therein to obtain a cardioid characteristic curve in the receivers. Energy from the aerial system is fed to the input elements of a receiver R by 40 means of a tuned inductance 9 variably coupled to an inductance 10 in series with the loop 1. To prevent the vertical component of the electric field of the wave from setting up circulating currents in the tuned circuit the entire loop circuit 45 including the coupling inductances is symmetrically balanced. This is attained by providing an inductance 11 electrically equivalent to the inductance 8 but in opposition thereto in series with the leads 12 and 13 connecting the inductances 50 10 and 8 in series with the loop 1. To further insure the complete balance of the apparatus the electrical midpoint of the inductance 10 is connected to ground through a connector 14.

For the sake of a more quantitative description of the various currents which may be produced in the tuned circuit 1, 2 of Figure 4 before the compensating electric pickup adjustments have been made and the arrangement has been properly balanced with respect to ground, 60 I will tabulate them as follows:

1. The normal loop effect

This is a voltage proportional to the rate of change of magnetic field linking the loop, and is 65 also proportional to the sine of the angle between the axis of the loop and the direction of the signals. This voltage produces a current in the same phase if the loop is tuned.

70 2. Effect of horizontal component of electric field

This is proportional to the electric field and

to the cosine of the angle between the loop axis and the signals and produces a current 90° out of phase with the voltage because the voltage is applied across the tuned circuit rather than in series in it. Thus, the current is in time phase with the normal loop effect current and as a result makes the zero position of the loop fail to coincide with the direction of signals.

80 3. Effect of vertical electric field

If the loop is not grounded at its electric center the vertical field will produce current in exactly the same fashion as discussed under item 2. However, since the vertical field will act the same way, whatever direction the signals are 90 travelling the current produced will be constant and its phase will be the same as the phase of the currents in items 1 and 2.

4. The effect of the tuned vertical aerial on the loop

If the auxiliary open antenna is tuned to the signal the current in its coil will be in phase with the electric field and hence the magnetic field of its coupling coil 5 will be in the same phase as the magnetic field of the incoming signals. Thus, the current in the loop circuit produced by the coupling inductance in the open antenna 5 will be in phase with the normal loop current and by adjusting the coupling to such a value 100 that the two currents are equal in amplitude a 105 cardioid diagram is obtained.

If this cardioid diagram is to be a perfect one, that is, if the system is to have a true pointing position it is, of course, necessary that the two 110 adjustments for wiping out currents produced by the electric field, items 2 and 3 above, should have been made, namely, the grounding of the loop circuit at such a point that no circulating current is produced by the vertical electric field, 115 and applying the compensating electric pickups as disclosed in this invention to insure that any horizontal component of the electric field will produce no circulating current in the tuned circuit.

After the aerial has been installed and the length of the conductors ascertained by trial using signals from a known source, the operation 120 of this system is the same as the operation of direction finders of this type known heretofore.

Having fully described my invention and the operation thereof, I claim:

1. In a directional aerial system the combination of a loop aerial of appreciable axial length, and a pair of crossed open ended linear conductors parallel with the axis of said loop, opposite ends of said conductors being connected to the ends of said loop aerial.

2. A directional aerial system comprising a frame aerial, a vertical aerial coupled thereto, means for insuring the electrical symmetry of said loop including a connection between the electrical midpoint of said loop and ground, a receiver coupled to said aerials, and means including a pair of crossed linear conductors parallel to the axis of said loop and connected to opposite ends of said frame aerial for preventing the horizontal component of a distorted wave front from setting up out of phase currents in said frame aerial.
